EDWIN C. HENN, OF CLEVELAND, OHIO.

SPARK PLUGS

1,087,892.

Specification of Letters Patent. Patented Feb. 12, 1914.

Application filed March 18, 1919. Serial No. 684,439.

To all whom it may concern:

Be it known that I, CHARLES E. TALBERT,
a citizen of the United States, residing at
Washington, in the District of Columbia,
5 have invented certain new and useful Im-
provements in Spark-Plugs, of which the
following is a specification.

This invention relates to spark plugs.

In the use of spark plugs for automobiles and other gas engines there is more or less difficulty experienced in providing for an efficient sparking to insure explosions in the engine cylinders. This difficulty is caused more or less by carbon forming on the sparking terminals, preventing a jump of a spark from one terminal to the other.

It is therefore the primary object of my invention to provide a spark plug having cooperating sparking terminals so formed and associated with relation to each other as to provide for a plurality of sparking surfaces whereby, whether from oil or the formation of carbon on the terminals, the surfaces of the terminals are more likely to be exposed so as to provide for sparking to explode the gases in the engine cylinder.

Another object of the invention is to provide a sparking plug having inner and outer terminals, the outer terminal being preferably spirally wound around the inner terminal in spaced relation to the latter with the coils of the spirally wound terminal preferably uniformly spaced from the inner coil so as to provide a plurality of sparking surfaces.

A still further object is to provide a spark plug embodying two terminals, one of which is spirally wound around the other in spaced relation thereto with the outer ends of the terminals so arranged that drippings from one terminal will not fall upon the other.

With the above and other objects in view the present invention consists in the combination and arrangement of parts herein-
45 after more fully described, illustrated in the accompanying drawings and particularly pointed out in the appended claim, it being understood that changes may be made in the form, proportion, size and other minor
50 details without departing from the spirit or sacrificing any of the advantages of the invention.

In the drawings:—Figure 1 is an elevation of one form of spark plug embodying my invention. Fig. 2 is a longitudinal sec-

tional view. Fig. 3 is a longitudinal sectional view of a modified form of the invention. Fig. 4 is an end view of the modified form of plug. Fig. 5 is an elevation of the body of the plug illustrating a side view of the terminals of the modified form.

Referring now more particularly to the accompanying drawings, it will be understood that my invention is applicable to any type of spark plug but for purposes of illustration, I have shown a common form of spark plug which, in this instance, consists of a body portion 10 having one end exteriorly screw threaded as at 11 for working fit in the usual spark plug opening of an engine cylinder, the latter not shown. The body 10 has an internal shoulder 12 for the support of the porcelain or other insulating member 13. This insulating member 13 is held tightly on the shoulder 12 by means of the nut 14 which has working fit with the internal screw threaded portion at the outer end of the body 10, as clearly shown in the accompanying drawings. On the outer end of the insulating member 13 may be secured in any suitable manner a brass or other cap 15 provided with a bead 16 which has a reduced neck portion 17 which may be embraced by the terminal of an electric current conductor in the usual manner. The insulating member 13 is provided with a longitudinal bore in which is fitted a conducting wire 18 which has its upper end upset at 19 and contacting with the brass cap 15. The upset end 19 of the wire 18 prevents the
burning out of the bore of the
85
80
85
90

latter from slipping out of the bore of the insulating member. One end of the conducting wire 18 projects beyond the end of the insulating member to form a sparking terminal 20. Secured to the body 10 is another 95 sparking terminal which in this instance is preferably of spiral form and providing a plurality of spaced coils 22 arranged one above another and which encircle a terminal 20 in spaced relation to the latter 100 with the coils preferably uniformly spaced therefrom. This terminal is preferably formed of very rigid, stiff wire and each one of these coils provides a sparking surface with the result that there is formed a plurality of sparking surfaces so that in the event of carbon forming on portions of the different coils there are still surfaces of one or more coils exposed to provide for the jump of a spark from one terminal to the 110

other to explode the gases in the engine cylinder.

The spirally wound terminal 20 is preferably composed of very stiff wire, and if desired, its outer extremity may be pointed as indicated at 20'. In any event, the coils of the spirally wound terminal are preferably uniformly spaced from the inner terminal 19 and has its outer end terminating within 10 the plane of its coils so that any drippings of oil which may flow down the spirally wound terminal will not fall upon the inner terminal and, whereby, drippings of oil flowing down the inner terminal will not fall 15 upon the spirally wound terminal.

In Figs. 3, 4 and 5 there is shown a modified form of the invention. In this instance, the plug may be of any suitable type, but, as shown, is like the plug illustrated in Figs. 20 1 and 2. In this different type of invention the terminals are the same except that the spirally wound terminal 23 has its lower coil directed outwardly as at 24, and then directed upwardly as at 25, and again outwardly, as at 26 with the part 26 secured to the plug in the same manner that the part 26 of the spirally wound terminal is secured to the plug. The parts 24 and 26 are disposed preferably at points apart a

distance of substantially or exactly one-quarter of the circumference of the inner end of the plug 10 to provide for a better bracing effect, if such should be necessary in certain types of engines, than would be afforded if the parts or ends 24 and 26 of the spirally wound terminal were disposed directly opposite each other across the inner end of the plug. 30 35

What is claimed is:—

A spark plug comprising a hollow body 40 whose inner end is circular, a terminal mounted in the hollow plug and projecting therefrom, a second terminal composed of a piece of conducting material coiled intermediate its ends for coöperation with the 45 first named terminal to provide a plurality of sparking surfaces and having its ends secured to the inner end of the body at points apart a distance substantially one-quarter of the circumference of the outer end of said body. 50

In testimony whereof I affix my signature in presence of two witnesses.

CHARLES E. TALBERT.
